FLEXIBLE PACKAGE FOR LIQUIDS

Stephen A. Van Mil, Jr., Union, N.J., assignor to Ivers-Lee Company, Newark, N.J., a corporation of Delaware

Filed Oct. 23, 1961, Ser. No. 67,215

Term of patent 14 years

(Cl. D58—2)

Fig. 1

Fig. 3

I claim:

The ornamental design for a flexible package for liquids, as shown and described.
